US00D699090S

(12) **United States Design Patent**
Kalajyan et al.

(10) **Patent No.:** **US D699,090 S**
(45) **Date of Patent:** **** Feb. 11, 2014**

(54) **KNIFE**

(75) Inventors: **Artem Kalajyan**, Burbank, CA (US);
Michael E. Henley, Liberty Township,
OH (US)

(73) Assignee: **JPJ Investment Holding Corp.**, City of
Industry, CA (US)

(**) Term: **14 Years**

(21) Appl. No.: **29/391,483**

(22) Filed: **May 9, 2011**

(51) **LOC (10) Cl.** **08-03**

(52) **U.S. Cl.**

USPC **D8/99**

(58) **Field of Classification Search**

USPC D8/95-99, 105, 107; D22/118;
30/154-162, 329-331

See application file for complete search history.

(57) **CLAIM**

The ornamental design for a knife, as shown and described.

DESCRIPTION

FIG. 1 is a perspective view of a knife in an extended position showing our new design;

FIG. 2 is another perspective view thereof;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a top plan view thereof;

FIG. 8 is a bottom plan view thereof;

FIG. 9 is a right side elevational view thereof in a retracted position;

FIG. 10 is a left side elevational view thereof;

FIG. 11 is a top plan view thereof;

FIG. 12 is a bottom plan view thereof;

FIG. 13 is a rear elevational view thereof; and,

FIG. 14 is a front elevational view thereof.

The broken lines illustrating a blade are directed to environment and form no part of the claim. All other broken lines in the drawings illustrate unclaimed features of the blade holder and the handle.

1 Claim, 8 Drawing Sheets
